UNITED STATES PATENT OFFICE.

SAMUEL E. SPERRY, OF HOLLIS, NEW YORK, ASSIGNOR TO INTERTYPE CORPORATION, OF BROOKLYN, NEW YORK, A CORPORATION OF NEW YORK.

MOLD FOR LINE-CASTING MACHINES.

Application filed May 22, 1928. Serial No. 279,733.

The present invention relates to improvements in molds for line casting machines and more especially molds of the general class used in machines of the type shown and described in Letters Patent No. 436,532 granted September 16, 1890, to O. Mergenthaler wherein the mold comprises members which form a slot or cavity in which a type bar or slug is cast, means being provided to 5 present a line of character bearing matrices to the front of the mold and the mouth-piece of a metal pot to the rear face of the mold, the metal injected into the mold slot or cavity from the metal pot casting a type bar 10 or slug therein bearing type characters along an edge thereof.

Heretofore, it has been customary to construct the mold with a body and a cap of varying cross sections both transversely and 20 longitudinally, and to secure the mold body to the mold wheel by an apron on the mold body which overlapped the face of the mold wheel and was secured thereto by screws, and to secure the mold cap to the mold body 25 by clamping screws which connected their ends, but such molds have presented the disadvantages that they or their parts were subject to warping, due to repeated heating and cooling thereof incident to the casting of 30 the type bars therein, with the result that the type bars were distorted or were not accurate in their dimensions.

The primary object of the present invention is to provide a novel and improved mold 35 of this general class which obviates the objections hereinbefore referred to and which affords advantages not present in molds of this class as heretofore proposed or used.

According to the present invention, the 40 mold is constructed of a mold body and a mold cap both of which are of substantially uniform cross section throughout both their longitudinal and transverse dimensions, thereby avoiding or minimizing warping of 45 these parts by stresses set up therein due to temperature changes.

Also, according to the present invention, 50 novel and improved means are provided for securing the mold parts to the mold wheel whereby substantially uniform stress is exerted thereby on all portions of the mold so that no portion of the mold will be without 55 direct support although all portions of the mold will be free to expand and contract,

both longitudinally and transversely, when 55 subjected to the varying temperatures existing in operation, distortion of the mold body and cap, due to the constraining influence of the mold securing means, being thereby avoided. 60

The present invention also provides a mold which is much less expensive to manufacture than the present forms of molds which, as is well known, are very costly.

A further object of the invention is to 65 provide a mold of the improved type referred to which can be applied to a mold wheel which may be interchanged with the mold wheel as ordinarily used in machines of this class, thus enabling the invention to 70 be applied to existing machines as well as new machines.

To these and other ends, the invention consists in certain improvements and combinations and arrangements of parts all as 75 will be hereinafter more fully described, the features of novelty being pointed out particularly in the claims at the end of the specification.

In the accompanying drawings:— 80

Fig. 1 is a front elevation of a portion of a mold wheel for a line casting machine of the type hereinbefore referred to, the mold wheel being equipped with a mold constructed in accordance with the present invention; 85

Fig. 2 represents a horizontal section taken on the line 2—2 of Fig. 1 and looking downwardly;

Fig. 3 represents a transverse section taken on the line 3—3 of Fig. 1 and looking 90 toward the right, the positions of the matrix line and metal pot mouth-piece relatively to the mold being indicated in dotted lines;

Fig. 4 is a front elevation of a portion 95 of the mold wheel and mold, showing the mold in vertical or slug ejecting position and illustrating devices provided to cause relaxation of the pressure on the type bar or slug cast within the mold in order to facilitate ejection of the type bar therefrom; 100

Fig. 5 is a view showing partly in section on the line 5—5 of Fig. 4 a portion of the mold wheel and the mold therein, in conjunction with the devices which cause relaxation of the pressure on the type bar or slug when the mold is brought into ejecting 105 position; and

Fig. 6 is a collective view showing in perspective the mold pocket in the mold wheel and the component parts of the mold adapted to be mounted therein.

Similar parts are designated by the same reference characters in the several views.

Molds embodying the present invention are applicable generally to line casting machines of the general class adapted to cast 10 type bars or slugs, and while the preferred embodiment of the invention is shown in the accompanying drawings and is hereinafter described in detail, it is to be understood that equivalent constructions are contemplated 15 and such will be included within the scope of the claims.

In the construction shown, 1 represents a portion of the mold wheel or disk of a line casting machine of the general class shown 20 and described in the patent hereinbefore referred to, the mold wheel being mounted on a shaft 2 whereby a mold in use on the wheel may be rotated to carry it from the horizontal or casting position to the vertical or 25 ejecting position, and may be returned from the latter position to the casting position, the periphery of the mold wheel being shown with gear teeth to cooperate with gearing whereby the mold wheel may be rotated at 30 appropriate times to bring the mold thereon in the different positions as described. The mold wheel shaft 2, in machines of this class, is mounted on a slide which moves forwardly immediately prior to the casting and ejecting 35 operations, the consequent forward movement of the mold wheel immediately preceding the casting operation bringing the mold into contact with the rear face of a line of matrices M which have been previously 40 lowered to a position level with and opposite to the forward face of the mold, after which the mouth-piece 3 of a metal pot is brought against the rear face of the mold and the metal pot plunger operates to inject 45 molten metal into the mold to cast a type bar or slug therein, after which the metal pot mouth-piece is retracted to disengage it from the mouth-piece and the mold wheel is retracted to disengage the mold from the 50 matrix line.

Following the casting operation, the mold wheel is rotated to carry the mold from the horizontal or casting position shown in Fig. 1 to the vertical ejecting position shown in 55 Fig. 4, the mold containing the type bar or slug which has been cast therein being positioned immediately behind a knife block 4 which contains knives which trim the flat sides of the type bar or slug while the latter 60 is being pushed forwardly edgewise from the mold and through the space between the trimming knives, by an ejector, and the forward movement of the mold wheel, which 65 takes place immediately prior to the ejecting operation, brings the mold into close

relationship with the trimming knives. The construction and operation of the parts as just described are well known to those skilled in the art or familiar with line casting machines of the general class shown and described in the patent hereinbefore referred to. 70

The mold wheel, according to the present invention is provided with a mold pocket 5 which is defined by a base or inner wall 6 which is located on a chord of the circular 75 mold wheel, end walls 7 which extend outwardly perpendicularly to the base 6 and an outer wall which is formed of a pair of inclined surfaces 8, these surfaces being preferably of equal length and inclining upwardly 80 from the ends toward the center of the mold pocket. The mold pocket is preferably formed as a slot-like opening through the mold wheel, the pocket being located within the circumference or rim of the wheel and 85 entirely surrounded by the web or body portion of the wheel. A flange 9 preferably extends inwardly for a suitable distance beyond the inclined surfaces 8, for a purpose 90 that will hereinafter appear.

The mold, in the preferred embodiment of the invention, comprises cooperative members 10 and 11 which form the mold slot or cavity between them, and wedges 12 which serve to lock the member 10 and 11 in cooperative relation. The mold member 10 serves as a mold body, it comprising a bar of metal the top and bottom surfaces of which are flat and parallel and the front and rear faces of which are parallel, the front face of this member being provided with a groove 13 to receive the lower rear lugs on the matrices in the matrix line and thereby align the matrices in front of the mold, the flat top face of the member 10 forming the lower wall of the mold cavity. The flat straight bottom surface of the member 10 is adapted to seat solidly and accurately on the bottom and inner wall 6 of the mold pocket, and suitable means is provided for securing 100 the mold member 10 in such position. Preferably a suitable number of screws 14 each having right and left hand threads thereon are provided for this purpose, two of such screws being shown in the present instance, 105 they being threaded upwardly into the bottom of the mold member 10 and downwardly into the inner or bottom wall 6 of the mold pocket at points intermediate the ends of the mold member, these screws having angular or other suitably shaped wrench-receiving portions 15 thereon which may be accommodated in recesses 16 formed in the inner wall 6 of the pocket, so that tightening of these screws will draw the 110 mold member 10 firmly and solidly against the inner wall 6 of the pocket and will secure said mold member in such position.

The mold member 10 is also provided with means for locking it against displacement 115

in the mold pocket in a forward or rearward direction, such means comprising in the present instance lugs 17 which project beyond the ends of said member and abut against faces 7^a adjacent to the front edges of the end walls 7 of the mold pocket, these faces being preferably recessed or offset rearwardly from the face of the mold wheel, the abutting of the lugs 17 against these faces preventing displacement of the mold member 10 in a rearward direction, and the lugs 17 engage the rear faces of flanges 18 which overlie or are opposite to the faces 7^a, the flanges 18 being formed on bosses which 15 may be cast integral with or suitably secured to the face of the mold wheel, the engagement of the lugs 17 with the flanges 18 preventing displacement of the mold member 10 in a forward direction. While the 20 flanges 18 will thus engage the lugs 17 on the member 10 when the latter is seated in the mold pocket, these flanges terminate at a sufficient distance from the upper or outer portion of the mold pocket to enable the 25 mold member 10 to be inserted into or removed from the mold pocket by a transverse movement of the lugs 17 above the flanges 18, and the lugs 17 are movable vertically between the flanges 18 and the faces 7^a during insertion and removal of this mold member. The 30 mold member 11 is constructed preferably of a bar of metal having parallel top and bottom and front and rear surfaces, the bottom surface of this member being finished so that it will accurately contact with the top face of the member 10 and thus form a metal tight joint therewith, and in the preferred embodiment of the invention, the member 10 is formed in its bottom face with a recess 35 19 the length, height and position of which conform with a mold cavity, and when the member 11 is mounted on the member 10 the bottom of this recess will be closed by the top surface of the member 10, and said recess 40 will then form the mold slot or cavity. The member 11 thus takes the place of the usual mold cap and separate liners, the present invention enabling a number of mold members 11 to be kept on hand, these members all 45 being of the same outside dimensions but having recesses of different lengths or heights to conform with type bars or slugs of different lengths or thicknesses which it may be desired to cast. The mold member 50 11 is provided at its ends with lugs 20 which are adapted to move vertically between the surfaces 7^a and 18 during insertion and removal of said mold member and when this mold member is mounted on the mold member 10, it is locked against forward or rearward displacement with respect thereto by the abutting engagement of the lugs 20 with the surfaces 7^a and the flanges 18. The mold member 11 is introduced into or removed 55 60 65 from the mold cavity by inserting its lugs 20

into the channels formed between the surfaces 7^a and the flanges 18 and lowering the member 11 on to the member 10 or lifting the member 11 until the lugs 20 thereon reach the tops of the flanges 18 whereupon 70 the member 11 can be withdrawn forwardly from the upper or outer portion of the mold pocket. The forward face of the member 10 is preferably provided with a pair of apertures 21 to receive the ends of a tweezers-like 75 tool the use of which will facilitate the removal of the member 11 especially while it is hot.

The mold member 11, in the preferred embodiment of the invention, is locked in co-operative relation with the member 10 by the wedges 12 which are adapted to be interposed between the upper or outer face of the member 11 and the reversely inclined outer surfaces 8 of the mold pocket. The 80 lower faces of the wedges are preferably aligned so that they will be movable longitudinally on the flat top face of the member 11 while the upper faces 22 of the wedges are bevelled or inclined to conform with the inclines of the respective surfaces 8, the downward slope of the surfaces 8 toward the ends of the mold pocket causing the wedges when spread apart or moved relatively in a direction away from one another, to exert 85 a compression on the member 11 which forces it against the opposed face of the mold member 10. Means is provided for automatically actuating or spreading the wedges to lock the mold components together 90 and in the mold pocket, such means comprising preferably a coiled compression spring 23 which is interposed between the inner or adjacent ends of the wedges and acts with an appropriate force to spread the wedges 100 or to move them away from one another, such movement of the wedges causing them to move longitudinally on the top face of the mold member 11 and toward the ends thereof, and the cooperation of the reversely 105 inclined top surfaces 22 of the wedges with the correspondingly inclined surfaces 8 of the mold pocket will force the mold member 11 solidly against the mold member 10 and the wedges will thus lock the member 11 110 115 solidly against the member 10. The wedges are preferably provided with apertures 24 to receive the ends of a tweezers-like tool whereby the wedges may be drawn together or toward one another, in opposition to the 120 action of the spring 23, and to be thus removed or inserted. The inwardly extending flange 9 on the mold wheel adjacent to the wedge-engaging surfaces 9 will prevent displacement of the wedges from the mold 125 pocket in a rearward direction, and suitable means, such as pins 25 depending from the wedge-engaging surfaces and engaging in longitudinal grooves 26 formed in the top surfaces 22 of the wedges is provided to 130

prevent forward displacement of the wedges, the pins 25 being disengaged from the grooves 26, when the wedges are drawn toward one another and thus permitting the 5 wedges to be withdrawn forwardly from the mold pocket. When the wedges are inserted into the pocket, the flange 9 will act as a stop which will insure registration of the grooves 26 in the tops of the wedges with 10 the pins 25.

Although the wedges act to lock the mold members 10 and 11 firmly together, it is desirable to relax the pressure of the mold members 10 and 11 on the type bar or slug 15 cast in the mold in order to facilitate ejection of the type bar or slug. For this purpose, means is provided which moves the wedges 12 relatively toward one another a sufficient distance to relax the pressure exerted 20 on the type bar or slug at the time the mold is brought into slug-ejecting position. Preferably, a pair of projections 27 are fixed to the knife block 4 so that they will project rearwardly therefrom in positions where 25 they will enter spaces at the ends of the wedges, the inner or wedge-engaging faces of these projections being rounded or bevelled as at 28 so that they will engage the respective ends of the wedges, as the mold 30 wheel advances and will shift the wedges relatively toward one another a sufficient distance to reduce the compression exerted on the mold member 11 thus allowing the mold member 11 to move slightly away from the 35 mold member 10 and thus relax the compression exerted on the type bar or slug. The latter may then be easily ejected from the mold by the usual ejector blade and pushed through the trimming knife for the trimming 40 of its flat sides. When the mold wheel is retracted, following the ejecting operation, the ends of the wedges are disengaged from the projections 27 and the wedge actuating spring 23 then acts to relock the mold members 10 and 11 under firm compression, preparatory to the next following casting operation.

By constructing the mold members 10 and 11 as blocks or bars of steel of substantially 50 rectangular uniform cross section throughout their length, as shown, warping of these parts, due to stresses set up therein by the temperature changes taking place during the use of the mold, is avoided to any appreciable degree, and by mounting these members 55 so that their end portions do not abut against the ends of the mold pocket but are free to move longitudinally within the pocket, these mold members will be able to expand 60 or contract without distortion. The wedges firmly hold these members of the mold in contact, but they merely bear on the longitudinal top surface of the member 11 and hence they will not interfere with thermal 65 expansion and contraction of these mold

members, although there will be a sufficient amount of yield or flexibility of the member 11 and its locking wedges to release the adherence of the type bar to the walls of the mold and to enable it to be ejected therefrom even though the wedges are not retracted, although it is preferable to retract the wedges during the ejecting operation, as such is thereby greatly facilitated.

The locking wedges are preferably sufficiently long to act on the member 11 substantially throughout its length, as they then act substantially uniformly upon all portions of the mold member to evenly press it against the body or base member 10, and they avoid causing sagging of the unsupported portion of the member 11 above the recess or mold cavity, as portions of the wedges will be opposite to the portions of the member 11 which bear directly on the base member 10.

By constructing the member 11 and its locking wedges so that they are readily removable from the mold pocket, although the base member 10 remains in position therein, the operator is enabled to easily and quickly remove a mold member having a recess of one length or depth and to substitute another member of the same vertical height or thickness but having a recess of different length or depth to produce type bars of a desired length or thickness. Although it is preferable to construct the member 11 so that it takes the place of the usual mold cap and separate end liners, as the cost of machining and finishing the surfaces is greatly reduced, it is to be understood that the other features of the invention may be used in conjunction with a mold cap and separate liners.

The provision of wedges having sloping surfaces of a suitably small angle in conjunction with the spring for spreading or expanding the wedges insures substantial uniform locking together of the mold parts, notwithstanding thermal expansion and contraction of these parts and the mold wheel, as the wedges acting under the yielding force of the spring will accommodate their extent of locking movement to the relatively expanded or contracted condition of the mold parts or mold wheel, so that the mold parts will not be too loosely held when said parts are relatively cool and contracted nor too tightly locked when the mold parts are relatively hot and expanded, and the wedges may spread under the action of the spring and thus automatically take up any slack or looseness that might develop. The small angle of slope of the inclined wedge surfaces precludes forcing together of the wedges and consequent release of the mold members, under expansive tendency of the mold.

I claim as my invention:—

1. A mold for line casting machines com-

prising cooperative members forming a slug casting cavity between them and having contacting surfaces which are flat and lie in the same plane throughout their extents, each of 5 said members being of substantially uniform cross section throughout its length and shiftable longitudinally relatively to the cooperating member, and means for holding said members in cooperative relation while allowing them to shift longitudinally relatively to one another to compensate for thermal expansion and contraction.

2. In a line casting machine, the combination of a mold support having a mold pocket 15 therein, cooperative mold members forming a slug casting cavity between them, means securing one of said mold members against one wall of the mold pocket, and means between the opposite wall of the pocket and 20 the other mold member operative to hold the mold members in cooperative relation while permitting them to shift relatively to one another to compensate for thermal expansion and contraction.

25 3. In a line casting machine, the combination of a mold support having a mold pocket therein, a mold embodying cooperative members mounted in said pocket, means for clamping said mold members together and 30 securing them in said pocket, and means at the ends of the pockets cooperative with the ends of the mold members to retain them against lateral displacement from the pocket while permitting them to expand and contract therein.

4. In a line casting machine, the combination of a mold support having a pocket therein, a mold contained in said pocket and comprising a body member having means for securing it in said pocket, and a cooperative 40 member removably mounted in said pocket, and means at the ends of the pocket for preventing lateral displacement of said cooperative mold member in said pocket.

45 5. In a line casting machine, the combination of a mold support having a pocket therein provided with flanges at its ends, a mold contained in said pocket and comprising a body member having means for securing it in said pocket, and a cooperative mold member removably mounted in said pocket and having portions toward its ends to cooperate with said flanges, when mounted in said pocket, to lock said cooperative 50 member against transverse displacement from the pocket.

60 6. In a line casting machine, the combination of a support having a mold pocket therein provided with flanges which overlie the face of said support adjacent to its ends, and a mold contained in said pocket and comprising cooperative members forming the mold cavity between them, said mold members having lugs at their ends engageable between the face of the support and the respec-

tive flanges for holding the mold against displacement with respect to the mold pocket.

7. In a line casting machine, the combination of a support having a mold pocket therein, a mold comprising body and cap 70 members forming a slug casting cavity between them, means between the body member and the respective wall of the pocket and engaging the body member at points between its ends for securing the body member in 75 the pocket, and means for holding the cap member in cooperative relation with the base member.

8. In a line casting machine, the combination of a mold support having a mold pocket 80 therein, a mold contained in said pocket and comprising a body member and a cap member, devices interposed between the mold body member and the respective wall of the pocket for drawing said body member 85 against said wall, and means interposed between the cap member and the opposite wall of the pocket for holding said mold members in cooperative relation.

9. In a line casting machine, the combination of a mold support having a mold pocket 90 therein, a mold comprising cooperative members contained in said pocket, and means including a wedge and yielding actuating means therefor normally acting to lock the 95 mold members in cooperative relation.

10. In a line casting machine, the combination of a mold support having a mold pocket therein, a mold contained therein and comprising body and cap members forming the 100 mold cavity between them, the wall of the pocket opposite to the cap member being inclined relatively to said member, wedge means interposed between the cap member and said inclined wall, and means normally 105 tending to actuate the wedge means to lock the mold members in cooperative relation.

11. In a line casting machine, the combination of a mold support having a mold pocket therein a wall of which is formed with 110 reversely inclined surfaces, a mold comprising superposed members contained in the pocket, wedges interposed between the mold and the respective inclined surfaces of the pocket, and means normally tending to move the wedges to lock the mold members.

12. In a line casting machine, the combination of a mold support having a mold pocket therein, a wall of which is formed with an inclined surface, a mold contained in the pocket, a wedge removably interposed between the mold and said inclined surface and operative to lock the mold, said surface having a retaining projection extending therefrom and the wedge having a recess to receive said projection when the wedge is in mold locking position, said recess being free of said projection when the wedge is in released position and permitting removal of the wedge from the pocket.

13. In a line casting machine, the combination of a mold support having a mold pocket therein a wall of which is formed with reversely inclined surfaces, a mold comprising superposed members mounted in said pocket opposite to said inclined surfaces, wedges interposed between the mold and the respective inclined surfaces and movable in one direction thereon to lock the mold members and in another direction to release the latter, and means interposed between said inclined surfaces and the wedges to retain the wedges against lateral displacement from the pocket when said wedges are in locking position and for releasing the wedges for removal from the pocket when said wedges are in released position.
14. In a line casting machine, the combination of a mold support having a mold pocket therein a wall of which is formed with reversely inclined surfaces, a mold comprising superposed members mounted in the pocket opposite to said inclined surfaces, a pair of wedges interposed between the mold and the respective inclined surfaces, and a spring connecting the wedges for actuating them, the angle of inclination of said inclined surfaces being sufficiently small in relation to the strength of said spring to enable the latter to actuate the wedges to lock the mold members in cooperative relation.
15. In a line casting machine, the combination of a mold support having a mold pocket therein, a mold comprising members forming the mold cavity between them, wedge means normally acting to lock the mold members in cooperative relation, the mold support being movable to bring the mold into slug ejecting position, and means operative during the movement of the mold into slug ejecting position for retracting the wedge means and thereby cause relaxation of the pressure of the mold members on the slug in the mold cavity.
16. In a line casting machine, the combination of a mold wheel having a mold pocket therein, a mold comprising members forming the mold cavity between them, means including wedges and a spring acting to actuate the wedges to normally lock together the mold members, the mold wheel being movable to carry the mold into casting and slug ejecting positions, and projections operative on the wedges to retract them and thereby relax the pressure of the mold members on the slug in the mold cavity when the mold is brought into slug ejecting position.

In testimony whereof I have hereunto set my hand.

SAMUEL E. SPERRY.
